Application June 30, 1943, Serial No. 492,806

16 Claims. (Cl. 66—86)

This invention relates to knitting machines of the warp type and is concerned more particularly with a novel warp knitting machine which can be operated at a higher output rate and runs more smoothly than prior similar machines, so that it is capable of producing fabrics of higher quality at lower cost. The advantageous results mentioned are derived from the use in the machine of a new and improved supporting structure which absorbs vibration and prevents transmission thereof between certain elements of the machine.

Warp knitting machines as now constructed include a machine frame on which are mounted one or more supplies of warp thread in the form of warp beams and knitting elements consisting of a needle bar, sinker bar, presser bar, and guide bar assemblies. These assemblies extend the full length of the machine, which may be from 6 to 15 feet in ordinary practice, and, during the operation of the machine, they are given rapid non-rotary movements by cams on a common driven shaft also mounted on the frame. In addition to a rocking movement about a longitudinal axis imparted to them by the cam shaft, the guide bar assemblies are also reciprocated endwise by a patterning or traverse mechanism attached to the frame, so that they may lap the threads about the needles in the desired manner. The traverse motions of the guide bar assemblies are produced by means of pattern cam wheels, which, although continuously driven, are of such shape as to cause the assemblies to move stepwise when they have been swung in front and to the rear of the needles.

To produce fabrics of high and uniform quality on such machines, it is essential that the knitting assemblies function smoothly and regularly. However, the mode of operation of the assemblies causes vibrational and twisting forces to be applied to the frame by the cam shaft and patterning mechanism and such forces, when transmitted to the assemblies through the frame, may cause impairment of the quality of the fabric. In addition, the development of those forces and their application to the frame imposes a limitation upon the speed at which the prior machines may be operated with safety. A further factor of importance in the situation is that the mounting of the warp beams on the frame results in a change in the center of gravity of the machine and a reduction in its stability, as the weight of the warp supply decreases during the production of the fabric.

In attempts to build warp knitting machines

capable of operating at a high rate of production, such as from 350 to 700 stitches a minute, efforts have been made to overcome difficulties arising from the development of the vibrational and twisting forces above mentioned by providing the machines with a rigid frame construction. In one prior machine, the frame has included vertical end frame members and one or more intermediate vertical frame members spaced apart and connected by short longitudinal members. The vertical frames afford support for the warp supply, the cam shaft, and the knitting assemblies and various shafts associated therewith, and one end frame supports the patterning mechanism. Such machines have not been satisfactory for high speed operation, because the complex harmonic forces originating in the cam shaft and its associated cams and the forces developed by the intermittent action of the patterning mechanism have caused the machine frame members to vibrate and have also resulted in the application of warping forces to the framework. These vibrational and other forces are then transmitted through the frame members to the knitting assemblies and interfere with the smooth operation thereof. While theoretically it is possible to construct a frame supporting the cam shaft, the knitting assemblies, the patterning mechanism, and the warp supply, which is of sufficient rigidity to prevent transmission of vibration from the cam shaft and patterning mechanism to the assemblies, in practice, such a frame construction cannot be built because of space limitations. Thus, if the height of the machine is kept within reasonable limits for accessibility to the knitting elements, space is not available for the use of the required number of vertical and horizontal members connected together in such fashion as to produce a rigid construction capable of absorbing vibrations when the machine is operated at the high speeds mentioned.

The present invention is, accordingly, directed to the provision of a novel warp knitting machine which overcomes the objections to the prior machines and is greatly superior thereto in that, by the use of a new frame construction, the vibrational and twisting forces developed by the cam shaft and patterning mechanism are kept from being transmitted through the frame to the knitting assemblies. At the same time, the new frame permits warp beams of any desired size to be used by making minor changes in the beam supporting structure and the beams are so supported that their decreasing weight during the

production of fabric does not affect the center of gravity of the machine and, therefore, does not impair the stability of the support for the knitting elements.

The new machine includes a frame comprising a massive integral base which extends the full length of the machine and on which the cam shaft and the patterning mechanism are directly supported. The knitting assemblies are supported on frame members mounted on the base and wholly independent of the support for the shaft and the patterning mechanism. The warp beams are supported in a separate frame construction which is so attached to the integral base that the weight of the beams is supported in part by the base and in part by the floor on which the base is mounted. With this construction, vibrational and other forces generated by the operation of the cam shaft and patterning mechanism cannot pass from their points of origin to the knitting elements, except along a path of which the base forms a part. Such forces are, accordingly, absorbed by the base and there is no transmission of the forces from the base to the knitting elements through the vertical frame members in any degree sufficient to impair the operation of the elements. Moreover, as the weight of the warp supply is not supported in any way by the frame members supporting the knitting elements, the changing weight of the warp supply is without effect on the center of gravity and stability of that portion of the structure on which the knitting elements are mounted.

For a better understanding of the invention, reference may be made to the accompanying drawings in which

Fig. 1 is a view of the new machine in front elevation;

Fig. 2 is an end view of the machine from the right-hand end of Fig. 1;

Fig. 3 is a sectional view on the line 3-3 of Fig. 1; and

Figs. 4 and 5 are enlarged sectional views illustrating the knitting assemblies and the mechanism by which they are operated.

The machine shown in the drawings includes a frame provided with a massive integral base 16 which extends the full length of the machine and is provided at intervals with upright projections 11 and 12. The base is supported on a floor by feet 13 attached to the base and resting on the floor at spaced points. The upright projections 11 and 12 of the base support the cam shaft 14 which is journaled in bearings 15 on those projections, and the projections also provide support for end frame members 16 at the ends of the machine and intermediate frame members 17. The frame members are cut away as shown in Figs. 2 and 3, so that the cam shaft and its bearings are wholly out of contact with the frame members.

The knitting elements of the machine comprise needle bar, sinker bar, presser bar, and guide bar assemblies supported by the end frame members and intermediate frame members attached to the base. The needle bar 18 extends the whole length of the machine and it is supported at various points by arms 19 fast on shaft 20 supported at its ends in bearings 21 attached to end frame members 16 and at intermediate points in bearings 22 mounted on the intermediate frame members 17. The sinker bar 23 also extends the full length of the machine and is supported at various points by arms 24 on shaft 25, supported at its ends in bearings 26 attached to end frame

members 16 and at intermediate points by bearings 27 mounted on the intermediate frame members 17. The presser bar 28 similarly extends the entire length of the machine and it is supported at various points by connections fast on shaft 29 supported at its ends in bearings 30 on end frame members 16 and at intermediate points in bearings 31 on intermediate frame members 17. The guide bars 32 and 33 extend the entire length of the machine and are secured by suitable connections to a shaft 34 supported in bearings 35 attached to a longitudinal member 36 which is, in turn, attached at its ends to end frame members 16 and at intermediate points to intermediate frame members 17.

During the knitting operation, oscillatory motion is imparted to the knitting assemblies by cams on cam shaft 14. The needle bar is actuated by oscillation of shaft 20 and, for this purpose, the shaft is provided with arms 37 having bifurcated ends carrying rollers 38 running on cams 39 on shaft 14. The sinker bar is actuated by oscillation of shaft 25 and, for this purpose, the shaft is provided with arms 40 having bifurcated ends carrying rollers 41 running on cams 42 on the shaft. Presser bar 28 is actuated by oscillation of shaft 29 and the shaft is provided with arms 43 terminating in bifurcated ends carrying rollers 44 running on cams 45 on the shaft. The guide bars 32, 33 are actuated by oscillation of shaft 34 and the shaft is provided with arms 46, each of which is connected by a link 47 to a lever 48 pivoted on shaft 20 and terminating in bifurcated ends carrying rollers 49 running on cams 50 on the shaft. In each instance above, the two rollers on an arm, such as rollers 38 on one of the arms 37, run on separate cams on the cam shaft, but only one such cam is shown for the sake of clearness.

The rotation of the cam shaft causes the various cams to impart the requisite non-rotary motions to the knitting assemblies and such motions result in the generation of vibrations. In the prior machines, the cam shaft is supported in bearings mounted directly on the end frame and intermediate frame members, with the result that vibrations and other forces originating in the shaft are transmitted directly through those frame members to the knitting assemblies. In the present construction, the cam shaft is supported directly on the base and the vibrational and other forces originating in the cam shaft are not transmitted through the frame members 16 and 17 to the knitting assemblies but, instead, are absorbed by the base.

The warp supply of the new machine may include one or more beams and, in the machine illustrated, the supply comprises two beams 51 and 52, which are supported by a structure separate and distinct from that in which the knitting assemblies are mounted. The beams are supported at their ends in suitable bearings in end frame members 53 held in position by attachment at points 54 and 55 to the end frame members 16. End frames 53 are supported in part by ledge 56 on the base 10, and a substantial portion of the weight of the warp supply and its supporting structure is carried by feet 57 attached to the lower ends of frame members 53 and resting on the floor. The warp beams are also supported at one or more intermediate points by bearings in an intermediate frame member 58, which is held in position by attachment at point 59 to the longitudinal girt 36. The frame member 58 is supported in part by a ledge 60 on the base 10 and

in part by a foot 61 beneath the lower end of the frame and resting on the floor.

The warp threads 62 and 63 drawn from the beams 51 and 52, respectively, pass over spring actuated tension bars 64 and 65 to thread guides 66 and 67 carried by the guide bars 32 and 33, respectively. The guides direct the threads to needles 68 carried on the needle bar 18 and the threads are knitted into the fabric by the interaction of the guides 66 and 67, the needles 68, the sinkers 69 on the bar 23, and the presser 70 carried by the bar 28.

During the knitting operation, each guide bar receives two kinds of motion during the knitting cycle, namely, rocking motion about shaft 34 to carry the threads back and forth between the needles, and an endwise patterning motion occurring when the thread guides are in front and to the rear of the needles, these motions lapsing the threads around the needles. The patterning motion is imparted to guide bar 32 by a connection 71 secured at one end to the guide bar and at the other end to a sliding plunger 72 mounted in a bracket 73. One end of the plunger is provided with a cam roller 74 bearing on the surface of a pattern cam wheel 75. To maintain the roller against the cam surface, a spring 76 is connected to the opposite end of the guide bar and to a bracket 77 fast on shaft 34. The cam 75 is fast on a shaft 78 mounted in bearings in a bracket 79 and actuated from cam shaft 14 through suitable gearing 80. The guide bar 33 is driven in like manner by a second patterning cam on shaft 78. Brackets 73 for plungers 72 and brackets 79 for shaft 78 are mounted on a support 81 which is supported on an integral extension 82 of base 10.

During knitting, the patterning cams are driven continuously by the gears 80 from the cam shaft 14, but their peripheral shapes are such that they impart a stepwise or intermittent motion to the guide bars when the latter are in the front and in the rear of the needles. In high speed operation, such intermittent motion produces vibrational forces and, in the prior constructions in which the patterning mechanism is carried directly by vertical side frame members, those vibrational forces are transmitted to the frame members and through them directly to the other knitting elements carried thereby. In the new machine, the patterning mechanism is carried by the integral base independently of the frame supporting the knitting assemblies so that any vibration developed in the patterning mechanism is absorbed by the base and is not transmitted through the frame members to the assemblies.

From the foregoing, it will be apparent that the manner of constructing the frame of the new machine provides a structure supporting both the cam shaft and patterning mechanism, by which vibrational and other objectionable forces are generated, and the knitting elements, which must be protected against such forces, in such manner as to prevent transmission of those forces from their points of origin to the elements. This result is attained by including in the frame structure a massive integral base and then mounting the cam shaft, the patterning mechanism, and the knitting elements independently on the base. With this arrangement, vibrational and similar undesirable forces generated by the shaft and mechanism pass therefrom to the base, where they are absorbed, and such forces do not pass from the base to the elements in undesir-

able degree, even though the machine is operated at high speed. The attainment of the result is further insured by maintaining the stability of so much of the structure as supports the assemblies, and this is accomplished by supporting the warp supply in such manner that variations in weight thereof during operation do not alter the center of gravity of the assembly supporting means. The new machine can, accordingly, be operated at higher speeds than prior machines without impairment of the quality of the fabric produced and in complete safety.

We claim:

1. In a warp knitting machine, the combination of an integral base extending the full length of the machine, supporting members mounted on the base and extending upwardly therefrom, knitting assemblies mounted on the members, and a cam shaft for driving all the knitting assemblies, the cam shaft being mounted directly on the base out of contact with the supporting members for the assemblies.
2. In a warp knitting machine, the combination of an integral base extending the full length of the machine, supporting members mounted on the base and extending upwardly therefrom, knitting assemblies mounted on the members, bearings mounted directly on the base out of contact with the supporting members for the assemblies, and a cam shaft driving all the assemblies and mounted in the bearings.
3. In a warp knitting machine, the combination of an integral base extending the full length of the machine, supporting members mounted on the base and extending upwardly therefrom, knitting assemblies mounted on the members, a cam shaft for driving all the knitting assemblies, the cam shaft being supported by the base out of contact with the supporting members for the assemblies, and a patterning mechanism mounted on the base out of contact with the supporting members and the cam shaft.
4. In a warp knitting machine, the combination of an integral base extending the full length of the machine, supporting members mounted on the base and extending upwardly therefrom, knitting assemblies mounted on the members, bearings mounted on the base, a cam shaft for driving all the assemblies, the cam shaft being mounted in the bearings out of contact with the supporting members, and a patterning mechanism mounted on the base out of contact with the supporting members and the cam shaft.
5. In a warp knitting machine, the combination of an integral base extending the full length of the machine, supporting members mounted on the base and extending upwardly therefrom, knitting assemblies mounted on the members, a cam shaft for driving the knitting assemblies, the cam shaft being supported by the base out of contact with the supporting members for the assemblies, and supporting members for warp beams, said members being arranged to transmit the weight of the beams partly to the base and partly to the supporting surface on which the base rests, whereby variations in weight of the warp supply do not substantially affect the center of gravity and stability of the structure comprising the knitting assemblies and their supporting members.
6. In a warp knitting machine, the combination of an integral base extending the full length of the machine, supporting members mounted on the base and extending upwardly therefrom, knitting assemblies mounted on the members, a cam shaft for driving the knitting assemblies, the cam shaft

being supported by the base out of contact with the supporting members for the assemblies, a patterning mechanism mounted on the base out of contact with the supporting members and the cam shafts, and supporting members for warp beams, said members being arranged to transmit the weight of the beams partly to the base and partly to the supporting surface on which the base rests, whereby variations in weight of the warp supply do not substantially affect the center of gravity and stability of the structure comprising the knitting assemblies and their supporting members.

7. In a warp knitting machine, the combination of an integral base extending the full length of the machine, knitting assemblies, a cam shaft for driving all the assemblies, and separate and independent means for supporting the assemblies and shaft from the base, whereby vibrations developed by the cam shaft and the assemblies during operation are transmitted directly to the base through the respective supporting means for the assemblies and shaft.

8. In a warp knitting machine, the combination of an integral base extending the full length of the machine, knitting assemblies including thread guide bars, a cam shaft for driving all the assemblies, and a patterning mechanism for controlling the operation of the thread guide bars, the knitting assemblies, cam shaft, and patterning mechanism being supported from the base wholly independently of one another.

9. In a warp knitting machine, the combination of an integral base extending the full length of the machine, vertical frame members on the base, knitting assemblies mounted in the vertical frame members, a cam shaft for driving all the assemblies and mounted on the base out of contact with the frame members, whereby vibrations developed by the cam shaft cannot be transmitted to the assemblies except through the base, and a patterning mechanism mounted on the base independently of the frame members and cam shaft.

10. In a warp knitting machine, the combination of an integral base extending the full length of the machine, vertical frame members on the base, knitting assemblies mounted in the vertical frame members, a cam shaft for driving the assemblies and mounted on the base out of contact with the frame members, whereby vibrations developed by the cam shaft cannot be transmitted to the assemblies except through the base, and supporting members for warp beams constructed to transmit the weight of the beams partly to the base and partly to the surface on which the base rests, whereby variations in the weight of the warp supply does not substantially affect the center of gravity and stability of the

structure comprising the knitting assemblies and their supporting members.

11. In a warp knitting machine, the combination of an integral base extending the full length of the machine, supporting members mounted on the base and extending upwardly therefrom, knitting assemblies mounted on the members, and a patterning mechanism mounted on the base out of contact with the supporting members.

12. In a warp knitting machine, the combination of an integral base extending the full length of the machine, supporting members mounted on the base and extending upwardly therefrom, knitting assemblies mounted on the members, a cam shaft for driving all the knitting assemblies, the cam shaft being supported by the base out of contact with the supporting members for the assemblies, and a patterning mechanism mounted on the base out of contact with the supporting members.

13. In a warp knitting machine, the combination of an integral base extending the full length of the machine, supporting members mounted on the base and extending upwardly therefrom, knitting assemblies mounted on the members, bearings mounted on the base, a cam shaft for driving all the assemblies, the cam shaft being mounted on the bearings out of contact with the supporting members, and a patterning mechanism mounted on the base out of contact with the supporting members.

14. In a warp knitting machine, the combination of an integral base extending the full length of the machine, supporting members mounted on the base and extending upwardly therefrom, a warp guide bar assembly mounted on the supporting members, and a cam shaft for driving the warp guide bar assembly and mounted on the base out of contact with the supporting members.

15. In a warp knitting machine, the combination of an integral base extending the full length of the machine, supporting members mounted on the base and extending upwardly therefrom, a presser bar assembly mounted on the supporting members, and a cam shaft for driving the presser bar assembly and mounted on the base out of contact with the supporting members.

16. In a warp knitting machine, the combination of an integral base extending the full length of the machine, supporting members mounted on the base and extending upwardly therefrom, a sinker bar assembly mounted on the supporting members, and a cam shaft for driving the sinker bar assembly and mounted on the base out of contact with the supporting members.

WILLIAM D. KELLOGG.
